UNITED STATES PATENT OFFICE

ERNEST TRAUTMAN, OF LAKEWOOD, OHIO, ASSIGNOR TO THE REPUBLIC BOX COMPANY, OF CLEVELAND, OHIO, A CORPORATION OF OHIO

REINFORCED MILK-BOTTLE CONTAINER

Application filed January 8, 1926. Serial No. 79,933.

This invention relates to containers such as commonly used for milk bottles and like receptacles which are adapted to be handled and stored in stacks.

5 The principal object of the invention is to provide an unusually sturdy construction whereby the containers may be subjected to considerable abuse without being weakened and becoming distorted.

10 A specific object is to provide a two part corner reenforce construction which parts may be easily applied to the corners of a rectangular shell formed of separate members already joined in such a manner that they may be conveniently handled as a unit.

15 My corner construction embodies a pair of formed sheet metal braces, one of which is placed within the corner of the shell and the other on the outside of the corner, both braces 20 extending along each adjacent side shell member for a little distance. The two members are joined to each other by fastening members such as rivets which pass through the material forming the shell or wall. One of these 25 corner members has an offset extension to provide for holding one container in place upon another when stacked and to assist in guiding such containers into registration with each other.

30 It is a further object to provide a reenforce member of such a shape that it may be easily drawn from sheet metal and have the desired strength and other characteristics which will later appear.

35 Other features of the invention will become apparent from the further description which relates to the accompanying drawing. The essential characteristics will be summarized in the claim.

40 In the drawing, Fig. 1 is a perspective of a complete container; Fig. 2 is a fragmentary cross-section through the corner reenforce construction; Fig. 3 is a diagrammatic representation showing the manner in which the 45 reenforce members are applied to the joined side wall portions of the container; Fig. 4 is a cross-section taken at right angles to Fig. 2 as indicated by the line 4—4 on Fig. 1.

50 Referring in detail to the drawings and indicating the various parts by suitable charac-

ters, 1 and 2 represent the side and end wall members of the container respectively. These members are built up preferably of suitable boards of convenient width, and the end members are provided with openings such as 3, 55 which form suitable handles. The four wall members are first joined as by nails 4 (Fig. 4) whereby the container may be conveniently stored after assembly up to this point and prior to applying the reenforce members. 60

The partition members which as shown comprise rods 5 joining opposite wall members are arranged in vertical rows running at right angles to each other to form cells. These rods are preferably riveted over at 65 their ends to prevent bending and to further strengthen the container. Certain of the rods, namely those at the bottom of the crate and designated 6 are spaced between the vertical rows of rods, and the milk bottles or articles 70 to be contained rest upon these rods 6.

In order that the rods 5 and 6 may be positively supported intermediately of their ends, I preferably provide a sheet metal partition member 7 which as shown extends across several of the rods running lengthwise of the container, openings 8 being provided one for each rod. The sheet forming the member 7 is curled over rods disposed perpendicularly to those which pierce the sheet, preferably a top 75 and bottom rod 5^a and 5^b respectively. The rods 5^a and 5^b which thus support the sheet also extend through the side wall members and are riveted at their ends. I have found that by this arrangement a very substantial 80 partition structure is provided, and the rods at the bottom are very effectively prevented from bending down under the weight of the articles contained. Such bending or sagging of these rods becomes serious in the ordinary 85 bottle container by reason of rubbing and wearing against other crates or against a floor along which the containers are sometimes slid.

The corner reenforce construction comprises in each case two sheet metal members 90 each bent substantially at right angles, one extending over the corner and along the edges of the container on the outside and the other extending along the inside of the corner. The outer reenforce, designated 10, consists as 100

shown of a bent strip 11 extending substantially the height of the container and then inwardly over the upper edge thereof at 12 to form a metal rest for another container 5 stacked thereon as above mentioned. It is incidentally immaterial whether the bent-over portion 12 is at the top or bottom of the container, and it is within the scope of my invention to thus turn both ends of the strip inwardly if desired.

As shown in Figs. 2 and 4, the outer reinforce is set into the wall material so that the edges of the metal are substantially flush with the walls of the container, both at the top 15 and at the sides. By reason of this construction there are no projecting cutting edges exposed at the corners and the appearance of the container is improved.

The inner reenforcing member 15 is bent 20 at an angle conforming to the interior of the box at its corner and the flanges so formed may be riveted to the opposite flanges of the member 10, such rivets passing through the walls 1 and 2 of the shell thus holding both 25 reenforce members in place with respect to the shell.

The upper end 16 of the member 15 extends above the upper edge of the container and is offset toward the theoretic center of 30 the container at 17 to provide clearance for the lower end of a similar reinforce on a container to be stacked thereon. The top of the portion 16 curves inwardly at 18 to form a crown whereby the containers to be stacked 35 one on another need not be accurately centered but will be cammed in place by this crown. I have found that material which may be obtained cheaply will suffice for this corner reenforce member without cracking 40 when being drawn, if shaped substantially as shown, namely with the adjacent edges 20 and 21 forming in effect intersecting convex curves, the point of intersection being above the rounded surface 18. If the material of 45 this crown were to extend directly across between the outer edges of the flanges, the metal would have a tendency to crack toward the rounded portion, whereas with this V effect there is no tendency for the metal to 50 crack even though the material used is inexpensive sheet metal.

It will be seen that I have provided a container which is exceptionally sturdy and in 55 which the partitions are not likely to get out of place or bent and the corners of which are so reenforced that the box is effectively prevented from becoming skewed. I am aware that containers with corner reenforcing 60 members having projections for aligning stacked containers have been previously used, but I believe the construction whereby an inner and outer reenforce may be riveted together upon the already formed shell, as 65 well as other features of the construction

which I have herein set out in detail, to be new.

I claim:—

In a bottle crate the combination of a plurality of wall members joined to form four 70 corners, an inner and outer corner reenforcing iron at each corner, said irons comprising L-shaped members extending from the top to the bottom of the crate, the inner iron being offset inwardly at the top to serve as a 75 guide for a superimposed crate, said outer iron having its top portion bent to overlie both adjacent walls, all portions of the outer iron being inset into the wall material in such manner that all the edges of the iron are flush 80 with the wall material and are effectively guarded by the wall material.

In testimony whereof, I hereunto affix my signature.

ERNEST TRAUTMAN.
